Primary Examiner — Keli L Hill*(74) Attorney, Agent, or Firm* — Condo Roccia Koptiw LLP(57) **CLAIM**

The ornamental design for a food and beverage can, as shown and described.

DESCRIPTION

FIG. 1 is a top perspective view of a food and beverage can according to our design;

FIG. 2 is a top plan view of the food and beverage can of FIG. 1;

FIG. 3 is a bottom plan view of the food and beverage can of FIG. 1;

FIG. 4 is front-side elevation view of the food and beverage can of FIG. 1;

FIG. 5 is a rear-side elevation view of the food and beverage can of FIG. 1; and,

FIG. 6 is a side elevation view of the food and beverage can of FIG. 1.

The longitudinal broken lines are included for the purpose of illustrating portions of the food and beverage can that form no part of the claim. The dot-dash lines of FIGS. 1, 2, and 3 illustrate boundaries of the claimed design.

1 Claim, 6 Drawing Sheets(56)
